UNITED STATES PATENT OFFICE.

ROLAND W. KNAPP, OF MINNEAPOLIS, MINNESOTA.

WATER-TUBE BOILER.

SPECIFICATION forming part of Letters Patent No. 651,366, dated June 12, 1900.

Application filed July 13, 1899. Serial No. 723,646. (No model.)

To all whom it may concern:

Be it known that I, ROLAND W. KNAPP, a citizen of the United States, residing at Minneapolis, in the county of Hennepin and State of Minnesota, have invented certain new and useful Improvements in Water-Tube Boilers; and I do hereby declare the following to be a full, clear, and exact description of the invention, such as will enable others skilled in the art to which it appertains to make and use the same.

My invention has for its object to generally improve the construction of so-called "water-tube" boilers; and to this end it consists of the novel devices and combinations of devices hereinafter described, and defined in the claims.

The invention is illustrated in the accompanying drawings, wherein like characters indicate like parts throughout these several views.

Figure 1 is a view in front elevation, showing a boiler constructed in accordance with my invention. Fig. 2 is a view of the said boiler, partly in rear elevation and partly in vertical section, on the line $x^2 x^2$ of Fig. 3, with some parts broken away. Fig. 3 is a longitudinal section taken approximately on the line $x^3 x^3$ of Fig. 1, some parts being broken away. Fig. 4 is a horizontal section taken approximately on the line $x^4 x^4$ of Fig. 3. Fig. 5 is a view in front elevation showing a modified form of my improved boiler, some parts being broken away. Fig. 6 is a side elevation of my improved boiler with some parts broken away. Fig. 7 is a horizontal section taken approximately on the line $x^7 x^7$ of Fig. 5. Fig. 8 is a transverse vertical section taken approximately on the line $x^8 x^8$ of Fig. 6, and Fig. 9 is a vertical section taken on the line $x^9 x^9$ of Fig. 8.

In all of the views above noted the outside casing of the boiler, which would usually be formed of metal plate, has been removed to better illustrate the internal construction of the boiler.

Referring first to the construction illustrated in Figs. 1 to 4, inclusive, the numeral 1 indicates the main or primary drum, which is extended transversely of the boiler and is adapted to contain both water and steam. The drum 1 is supported by and opens into a pair of depending water-stacks or large feed-pipes

2, which in turn open at their lower ends one into each of a pair of long tubular water-drums or downflow-columns 3. Extending horizontally and parallel to each other and to the extended arms 3 is a pair of steam-return drums 4, which are in the form of long tubes and open into the said main or primary drum 1 above the level of the water z . It will of course be understood that any greater number, or even a less number, of the drums 3 and 4 and stacks 2 may be employed.

A closely-spaced series of transversely-extended manifold pipes or tubes 5 open from 65 and are secured to the upper pair of steam-drums 4, as best shown in Fig. 3. Opening at their lower ends into each of the water-drums 3 is a series of closely-spaced vertical feed-tubes 6, which, as will be presently noted, 70 constitute the sides of the fire-box. The opposite pairs of tubes 6 are connected at their upper ends by transversely-extended and closely-spaced manifold-tubes 7, which constitute the top of the fire-box. The manifold 75 tubes 5 and 7, which stand directly in vertical line, are connected by steam-generating tubes or pipes 8. These tubes or pipes 8 are formed by sections that extend approximately at right angles to each other and approximately at an angle of forty-five degrees to the horizontal. As shown, the section of the tubes 8 are joined by elbows 9, although they might be formed of single pieces of tubing bent at their elbows. All of the upper sections 80 of the said tubes 8 extend parallel to each other, and likewise all of the lower sections extend parallel one to the other. A horizontally-extended baffle-plate or partition 10 is extended around the tubes 8, just below 90 their elbows 9, so as to form a partition which will cause the flame or products of combustion to pass completely under the same and into the opening or chamber indicated at 11 before coming into contact with the upper sections of 95 said tubes 8.

Several of the tubes 8, or rather several transverse series of the same, which are at the extreme right in Fig. 3, instead of joining with manifold-pipes 7 are extended downward and united to manifold-pipes 7'; that are directly connected to the longitudinally-extended water-drums 3. Again, several transverse series of the tubes 8, which extend

to the extreme left in Fig. 3, or at the front end of the boiler, are connected to manifold-tubes 7^b and 7^c, the former of which are connected by a laterally-spaced pair of tubes 12 with the forward ends of the water-drums 3, while the said manifold-tubes 7^c are connected by tubes 13 with the forward end of the steam-drums 4. The upper ends of the said pair of vertical tubes 12 open into the ends of a transverse manifold-tube 14, while the lower ends of the vertical tubes 13 open into a similar transversely-extended manifold-tube 15. The manifold-tubes 7^b and 14 are closely spaced, while the said manifold-tubes 7^c and 15 are closely placed. A closely-placed series of vertical tubes 16 extend between the transverse manifold-tubes 14 and 15. Preferably the tubes 16 are bent, as shown at 17, to provide for expansion. As shown, the adjacent tubes 16 are bent the one at its upper end and the other at its lower end, as best shown in Fig. 3.

The grate 18 is suitably secured, as shown, by brackets 19 on the water-drums 3, and the combustion-chamber is of course formed immediately above this grate 18 and below the closely-spaced series of transversely-extended manifold-tubes 7. Of course if oil or liquid fuel or a gas were to be used with the boiler 30 the grate 18 would be dispensed with and suitable burners substituted therefor.

A transversely-extended manifold-tube 21 extends between the water-drums 3, just inward of the water-stacks 2, and another transversely-extended manifold-tube 22 is connected to the main or primary drum 1, above the water-level thereof, by means of several short tubes or pipes 23. A closely-spaced series of slightly-bent but upright tubes 24 connect the manifold-tubes 21 and 22 and fill in the space between the water columns or stacks 2.

In the illustration given water is supplied to the boiler through an inlet-pipe 25, which opens into the upper end of one of the water columns or stacks 2, as shown in Fig. 3. Also, as shown in Fig. 3, steam is delivered from the upper portion of the drum 1 through a pipe 26.

With the apparatus above described the action will be substantially as follows: A fire being lighted on the grate 18, the flame will pass rearward, or as indicated by the arrow marked *y* on Fig. 3, and will be caused to take a zigzag course between the vertical sections of the several rear end series of generating-tubes 8 and will then pass into the opening or chamber indicated at 27. The flame will of course be stopped by the closely-positioned series of vertical tubes 24 and will then be directed forward, as indicated by the arrow *y'*, and will be caused to take a zigzag course between the lower inclined sections of the tubes 8. The natural tendency of the flame or hot gases is of course to rise; but this tendency is nearly or quite overcome by the inclination of the said tube-sections, which on

account of their incline continuously deflect the said flame or gases downward, with the result that they will be passed between the 70 said inclined tube-sections on approximately horizontal lines. This feature of construction I consider broadly new, and it is of great importance, as it distributes the flame or burning gases evenly over all parts of the water-tubes. 75 After passing between the lower sections of the water-tubes 8 the products of combustion or flame will pass into the opening or chamber 11 and from thence will be turned backward, as indicated by the arrow *y²* in Fig. 3, 80 and will be caused to take a zigzag course between the upper inclined sections of the tubes 8 and will be again subjected to the downwardly-deflecting action of the said inclined sections, with a repetition of the result just 85 noted. After passing through the upper sections of the said water-tubes the flame or product of combustion will pass, as indicated by the arrow *y³* on Fig. 3, between the bottom of the main drum 1 and the adjacent upper sections of the tubes 24, and from thence they will be carried off in any suitable manner and by any suitable means. (Not shown.)

The reversely inclined or bent tubes 8 may expand unevenly without bad results, and this is a very essential feature in a boiler of this character. The manifold-tubes 5, 7, 7^a, 7^b, and 7^c are shown as provided with removable plugs 29, which when removed permit the insertion of a flue-cleaner into the tubes 100 8. Also, as shown, the tubes 24 are provided in their ends with removable plugs 30, which when removed permit the ready insertion of a flue-cleaner. Again, the transverse manifold-tubes 7, 7^a, 7^b, 7^c, 14, 15, 21, and 22 are 105 shown as provided with end plugs 31, which when removed permit the said tubes to be cleaned. The so-called "water-drums" 3 are also shown as provided in their forward ends with openings closed by ordinary hand lids, 110 plates, or covers 32.

In Figs. 5 to 9, inclusive, a construction is illustrated which embodies many of the features of construction above described in connection with Figs. 1 to 4, inclusive, but which is, however, a more intricate construction, being what may be well termed a "duplex water-tube boiler," involving a duplication of the construction illustrated in Figs. 1 to 4, inclusive, in bisymmetrical arrangement. In this construction the main or primary steam and water tank *a* is extended from front to rear of the boiler and is provided at its sides with a plurality of elongated steam-drums or large return-tubes *a'*, which correspond to 125 the so-called "drums" 4 of the previously-described construction. In the illustration given there are three of these drums *a'* projected from each side of the main drum *a*. From the bottom and rear end of the main drum *a* depends a large water stack or down-flow-column *a²*. (Best shown in Figs. 8 and 9.) The lower end of this water stack or column *a²* opens into the intermediate portion

of a long transversely-extended water-drum a^3 , which in turn opens on each side of its center into one of a pair of parallel and longitudinally-extended drums or supply-tubes a^4 . Each water drum or tube a^4 is provided with several—as shown, two—short and transversely-extended stub tubes or drums a^5 , the inner ends of which are spaced apart to make room for the grate b , which is suitably secured between them and immediately below the primary drum a . The forward members of the so-called “stub-drums” a^5 are connected by large and inclined downflow-tubes a^6 with the lower and forward portion of the primary drum a . A plurality of vertical tubes c and c' open upward from the central portion of the long transversely-extended drum a^3 , said tubes being closely spaced, so that they constitute a portion of the back wall of the fire-box or combustion-chamber b' , which is formed just above the grate b . As shown, the two central tubes c open into the bottom of the primary drum a , while the tubes c open into the rear ends of a series of longitudinally-extended manifold-tubes c^2 . At their forward ends the manifold-tubes c^2 open into a short transverse tube c^3 , which in turn is connected to the forward and bottom portion of the primary drum a by a short depending tube c^4 . (Best shown in Figs. 5, 6, and 9.) Longitudinally-extended series of manifold-tubes f connect the three steam-drums a' on either side of the main drum a . The two stub-drums a^5 are connected together and to the corresponding end of the long drum a^3 by the longitudinally-extended series of manifold-tubes f' . As shown, there are four of the vertical water-tubes c on each side of the two water-tubes c' , and the manifold-tubes c^2 , to which these tubes c are connected, are in turn connected to the four corresponding upper manifold-tubes f , each by a series of inclined tubes or flues g . The innermost lower manifold-tubes f' are connected to the lower ends of a series of generating-tubes g' . These two series of tubes g' are inclined toward each other and toward the center of the boiler and are then overlapped in close engagement at their central section, so as to form a top to the fire-box, and then are inclined or turned upward, so as to extend parallel to the corresponding inclined tubes g , and are then in the illustration given tapped into or connected to the fifth manifold-tube f , counted from the center of the boiler outward. Thus the tubes g' are spaced apart approximately the diameter of the pipes themselves at their upper and lower inclined extremities, but are placed tight together at their overlapped and horizontally-extended intermediate portions. The remaining manifold-tubes f and f' are connected in upper and lower pairs by a series of inclined generating-tubes g^2 . The upper and lower sections of these tubes g^2 are inclined reversely at approximately ninety degrees to each other or forty-five degrees to a horizon-

tal, and horizontal baffle-plates or partitions k separate the said upper and lower sections, as best shown in Fig. 8. The several series made up by the tubes g , g' , and g^2 are so set that the flame in passing between them will be caused to take a zigzag course. The spaces left in the rear end of the fire-box b' between the vertical tubes c and the inclined tubes g' may be filled in with brick, as indicated at k' . k^2 indicates inclined baffle-plates, which depend from the steam-drums a' just inward of the upper portions of the inner series of tubes g .

At the sides of the boiler, extended longitudinally of the same or from front to rear of the boiler, are upper and lower manifold tubes of large size, (indicated, respectively, by the characters n and n' .) These manifold tubes n and n' are connected, respectively, to the outer ends of the upper drums a' and to the outer ends of the lower drums a^3 and a^5 by short connecting-pipes n^2 and n^3 . The tubes n and n' are connected by closely-placed vertical tubes n^4 , and they are also connected by a laterally-spaced series of L-shaped tubes n^5 . In the illustration given triangular coils n^6 are placed in the opening or chamber n^7 , formed between the coöperating series of tubes n^4 and n^5 .

Under the action of the heat the circulation of the water will of course always be upward through the so-called “generating-tubes,” upon which the flame or products of combustion act directly, thus giving a very rapid circulation. On the other hand, the downward flow of the water through the so-called “downflow-columns” (these downflow columns or tubes in all cases being relatively large as compared with the generating-tubes and being located remote from the direct action of the flame or products of combustion) will be slow, so that the sediment will be deposited to a very large extent in the horizontal water-drums, from which it may be readily removed.

Referring again to the construction illustrated in Figs. 1 to 4, inclusive, attention is called to the fact that the staggered vertical lower ends of the several rear generating-tubes serve to thoroughly mix or commingle the fuel-gases before they reach the expanded portion 27 of the combustion-chamber. This action has its obvious importance.

With the construction illustrated in Figs. 5 to 9, inclusive, the flames will be drawn in two directions, or, in other words, the products of combustion will be divided and passed one part toward one side and the other part toward the other side of the boiler, and the courses which they will take in passing between the steam-generating tubes will be substantially as indicated by the several arrows marked on Fig. 8. All the advantages incident to the inclination of the various steam-generating tubes and to other features of construction particularly noted in connection with the construction illustrated in Figs. 1 to

4, inclusive, are found in this arrangement illustrated in Figs. 5 to 9, inclusive. This latter-described construction is, however, the better adapted for boilers of very high capacity.

Both of the constructions illustrated, but particularly the latter noted, are especially adapted for use as marine boilers, inasmuch as they are capable of being spread out and located close to the floor-line, so that their centers of gravity are thrown very low.

By the described arrangement of the steam-generating tubes the amount of heating-surface exposed to the flame or products of combustion is increased to the maximum and the surface is exposed in the most advantageous manner. Again, with the construction illustrated in Figs. 5 to 9, inclusive, the disposition of the steam-generating tubes and of the fire-grate makes it possible to use a main or primary drum or boiler of very large size and at the same time to keep its center of gravity very low. It also makes possible easy access to the manifold and generating tubes for the purpose of inspection or removal. The feed-water coils n^5 illustrated in this construction lead from a pump or other source of water-supply and lead to the main or primary boiler, this latter connection not being shown in the drawings.

From the foregoing description and statements made it will of course be understood that my invention is capable of many modifications not herein specifically mentioned. 35 The so-called "horizontal" baffle-plates or partitions k would in actual practice preferably be made in sections, so as to permit of the ready removal of any one or more sections of the generating-tubes.

40 What I claim, and desire to secure by Letters Patent of the United States, is as follows:

1. In a boiler, the combination with a combustion-chamber or draft-passage having approximately-parallel upper and lower walls 45 extended approximately in a horizontal direction, of a plurality of generating-tubes therein inclined downward in the direction of the draft therethrough, substantially as described.

50 2. In a boiler, the combination with a horizontally-extended combustion-chamber or draft-passage, of the plurality of generating-tubes 8, the upper and lower sections of which extend approximately at right angles to each 55 other, and are inclined downward in the di-

rection of the draft, and the horizontally-extended partition or baffle-plate 10 separating the upper and lower sections of said generating-tubes 8, substantially as described.

3. In a boiler, the combination with a steam-60 drum and a water-drum, the former located above the latter, of a series of manifold-tubes connected with said steam-drum, another series of manifold-tubes connected with said water-drum, and the several series of generating-tubes located in the combustion-chamber or draft-passage formed between the upper and lower series of said manifold-tubes, which generating-tubes are inclined downward in the direction of the draft, substantially as described.

4. In a boiler, the combination with a steam-drum and a water-drum, the former located above the latter, of a transverse series of manifold-tubes connected to said steam-drum, 75 a lower transverse series of manifold-tubes connected to said water-drum, the several series of generating-tubes connecting the upper and lower series of said manifold-tubes, said generating-tubes being reversely inclined in the direction of the draft, at their upper and lower sections, and a horizontal partition or baffle-plate separating the upper and lower sections of said generating-tubes, substantially as described.

5. In a boiler, the combination with the steam-drum 1 having the pair of depending water-stacks 2 opening at their lower ends into the horizontal water-drums 3, said drum being also provided with the pair of horizontal steam-return drums 4, of the series of manifold-tubes 5 connecting said return-drums 4, the series of transverse, manifold-tubes 7 connected to said water-drums 3 at their ends, by the vertical tubes 6, the plurality of reversely-inclined series of generating-tubes 8 connecting the said manifold-tubes 5 and 7, and the horizontal dividing partition or baffle-plate 10 separating the upper and lower sections of said tubes 8, but leaving communicating passages to and from the horizontally-extended draft-passages formed above and below said partition 10, substantially as described.

In testimony whereof I affix my signature 105 in presence of two witnesses.

ROLAND W. KNAPP.

Witnesses:

MABEL M. MCGRORY,
F. D. MERCHANT.
